UNITED STATES PATENT OFFICE.

SWAN PEARSON, OF YOUNGSTOWN, OHIO, ASSIGNOR OF ONE-HALF TO OSCAR L. GOLLA-DAY, OF YOUNGSTOWN, OHIO.

ATTACHMENT FOR WRITING IMPLEMENTS.

Application filed September 7, 1927. Serial No. 217,925.

This invention relates to an attachment for writing implements.

One object of the invention is to provide a simple, inexpensive, durable, effective and ornamental device of the nature stated, embodying among other characteristics, a member adapted for the support or suspension of the device from the wearer's pocket, and which member performs also the function of 10 a hand grasping piece to manipulate one of the elements of the device and constructed to exert such resistance to accidental movement of such element as to require the manual movement thereof against the resistance 15 offered thereby.

Another object of the invention resides in the provision of a device constructed to be readily attached to a writing implement or to have the latter attached thereto and including a sheath and a cutting element normally confined therein and arranged for projection therefrom by means adapted also for the purpose of supporting or suspending the device from a garment of the user.

25 A still further object of the invention is to provide a combination device including a writing implement holding part, a sheath, a blade normally confined within the sheath and adapted to be projected therefrom and 30 supported thereby for use, means whereby to support the device from a garment of the user when not in use and connected with the blade to project and retract the latter with relation to the sheath, and measuring graduations carried by the sheath.

With the above and other objects in view, the invention consists in the construction and novel combination and arrangement of parts hereinafter fully described, illustrated in the 40 accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Fig. 1 is a perspective view of the invention.

Fig. 2 is a plan view of the front of the device, illustrating the blade projected and the device removed from the pencil.

Fig. 3 is an enlarged longitudinal sec- 55 tional view on the line 3-3 of Fig. 1.

Fig. 4 is a plan view of the rear side of the device applied to a pencil and showing the graduated measuring scale.

Referring now more particularly to the accompanying drawing, the reference character 5 indicates, generally, the present invention, which is composed preferably of sheet metal folded longitudinally upon itself to provide at one side a relatively flat, shallow open ended sheath 6 and a sleeve 7 at its opposite side to receive a pencil 8 or other writing implement which is adapted to fit snugly in the sleeve, but which may be withdrawn therefrom when desired, the sleeve being at intervals, notched as indicated at 9, 70 to render the same more or less flexible so as to accommodate writing implements of different cross sectional diameters.

The sheath is provided on one side with a longitudinal slot 10, which terminates at 75 its ends adjacent the ends of the sheath, the ends 11 and 12 of the slot forming stops for a purpose presently explained.

A knife blade 13 is slidable in the sheath and adapted to be projected therefrom through one open end of the sheath and to be retracted readily. To this end, there is a member consisting of a hook 14 and a shank 15 connected to the blade, with a plate 18' therebetween. Two screws 16, 85 work through openings 17 in said shank 15 and extend through openings 18 in the plate 18' and into the threaded openings 13' in the blade 13, forming a detachable connection between said member and said blade. 90 Thus, by movement of said hook member, the plate 18' is caused to slide in said slot 10 to guide the movement of the blade. This connection is such that the blade and hook and shank member permit positioning 95 of the blade to project the same through either open end of the sheath 6, as may be preferred.

The hook 14 is adapted to engage over the top edge of a pocket of a garment whereby the user may readily support or carry the device on his person. The hook has still another function in that it provides a grasping piece whereby to project and retract the blade with relation to the sheath. Still another function is attributed to this hand grasping supporting hook and this is seen in the deflection of the back of the hook, as at 19, the deflected back being normally offset with relation to the slotted face of the 110

sheath, resulting in the deflected back, upon movement of the hook member to project the blade, to ride up over the end of the sheath and against and upon the slotted face 5 of the sheath, creating spring pressure which resists slightly the outward thrust of the blade, thereby preventing accidental projection of the blade when the device is supported from the wearer's pocket, and yet 10 permitting ready manual rearward projection of the blade against the slight resistance.

The shank 15 has its inner portion of a width to ride along the slotted face of the 15 sheath adjacent the longitudinal edges of the slot 10 as does also the back of the said hook. The shank tapers at its free end beyond said fastening screws 16 to a width substantially the width of the slot 10 of the 20 sheath and slides in the slot and at its extremity it is folded back upon itself to form a shoulder 17' which is adapted to ride over the stop 11 of the slot 10 slightly beyond the adjacent end of the sheath to slightly resist inward movement of the blade when the latter is retracted. The plate 18' at one 25 end engages the stop 11 to arrest and limit outward projection of the blade and to position said shoulder of the shank at the adjacent end of the sheath when the blade is projected. The other end of the plate 18' is adapted to engage the other stop 12 of the slot 10 to arrest and limit the inward 30 movement of the blade. The face of the slotted side of the sheath adjacent each end of the slot is beveled, as at 20 and 21, to facilitate movement of the deflected back of the hook and shoulder 17' over the respective 35 stops formed at the ends of the slot 10.

40 The side of the sheath opposite the side in which the slot 10 is formed is provided with measuring graduations 22 of any suitable character, and it will be understood that the finished article is nickled or otherwise highly 45 polished to give ornamentation to the device.

From the foregoing, it will be seen that the deflected back of the hook 14 resists slightly the movement of the hook up onto the slotted face of the sheath and that when 50 forced upon the slotted face of the sheath, the shank 15 between the hook and the fastening screws 16, is slightly bowed, as at 23, effecting spring pressure between the hook and sheath, and the blade being connected 55 to the shank there is a slight manual thrust necessary to project and retract the blade, thus preventing accidental slipping movement of the blade. It will also be apparent that the shoulder at the free end of 60 the shank offers resistance to retraction of the blade.

What is claimed is:

1. An attachment for writing implements comprising a piece of sheet metal folded 65 longitudinally upon itself to provide at one

side a relatively shallow open ended sheath and at its other side a sleeve to receive a writing implement, one side of the sheath having a longitudinal slot therein, a blade 70 slideable in the sheath through one end thereof, and a combined supporting hook member and shank detachably connected intermediate of its ends to the blade through said slot and arranged for slideable movement on the slotted side of the sheath 75 whereby to project the blade from the sheath or to retract the blade into the sheath, the fastening connection between the hooked element and the blade being engageable with the ends of said slot to limit the 80 inward and outward movement of the blade and the combined hook and shank member yieldingly engaging the slotted face of the sheath on opposite sides of said connection between the same and the blade 85 to thereby give frictional resistance to the movement of the blade.

2. An attachment for writing implements comprising a piece of sheet metal folded longitudinally upon itself to provide at one 90 side a relatively shallow open ended sheath and at its other side a sleeve to receive a writing implement, one side of the sheath having a longitudinal slot therein, a blade slideable in the sheath through one end 95 thereof, a member connected to said blade including a hook and shank arranged for slideable movement along the longitudinal edges of said slot whereby to project the blade from the sheath through one end thereof and to retract the blade into the sheath, said hook lying normally beyond the inner end of the sheath and being deflected to cause the back thereof to ride upon and frictionally engage the inner end of the 100 sheath to slightly resist outward movement of the member and consequent projection of the blade whereby to prevent accidental projection of the blade from the sheath, the sheath having measuring graduations thereon and said sleeve being notched to render the sleeve flexible to receive writing implements of different cross sectional diameters. 110

3. An attachment for writing implements comprising a sheath and a sleeve, the latter 115 to receive the writing implement, the sheath having a longitudinal slot in one side thereof, a blade slideable in the sheath through one end thereof, a member consisting of a hook and a shank connected to 120 said blade through said slot, the hook forming a supporting element for the attachment and also forming a hand grasping piece whereby to project or retract said blade with 125 relation to the sheath, said hook lying normally beyond the inner end of the sheath and adapted to ride upon the inner end of the sheath and exert pressure against the slotted face of the sheath to thereby give frictional resistance to the movement of the 130

same and the blade during manual manipulation thereof.

4. An attachment for writing implements comprising a sheath and a sleeve, the latter to receive the writing implement, the sheath having a longitudinal slot in one side thereof, a blade normally confined within the sheath and slideable in the sheath through the outer end thereof, a member consisting of a hook and a shank connected to said blade through said slot, the hook forming a supporting element for the attachment and also forming a hand grasping piece whereby to project or retract said blade with relation to the sheath, said hook lying normally beyond the inner end of the sheath and adapted to yield and ride upon the sheath to yieldably slide thereon to give frictional resistance to the movement of the same and the blade during outward movement of the blade, the free end of the shank being reduced in width and movable in the slot of the sheath and adapted to yield and ride out of the slot on to the outer end of said sheath and engage the outer surface of the sheath to thereby frictionally resist inward and outward movement of the blade, the connection between the hook-shank member and the blade being engageable with the opposite ends of said slot to limit inward and outward movement of the blade.

5. An attachment for writing implements comprising a sheath and a sleeve, one side of the sheath having a longitudinal slot therein, a blade normally confined within the sheath and slideable through the outer end of the sheath, and means, including a hook and a shank, the latter connected to the blade through said slot, for sliding the blade out of and into the sheath, said hook lying normally beyond the inner end of the sheath and adapted to yieldingly ride upon and over the inner end of the sheath and slide upon the slotted face of the sheath, exerting frictional resistance to the outward movement of the blade, the said shank at its outer end lying normally within said slot against the blade and upon reaching the outer end of the slot during outward movement of the blade yieldingly riding over the outer end of the slot on to the face of the sheath to give frictional resistance to the outward movement of the blade and also to thereby offer frictional resistance to an inward movement of the blade, the free end of said shank being folded back upon itself to form a shoulder adapted to lie against the outer end of the sheath when the blade is fully projected, the connection between the hook and shank and the blade being located to engage the ends of the slot in the sheath, interchangeably, to limit the inward and outward movements of the blade.

6. An attachment for writing implements comprising a sheath and a sleeve, one side of the sheath having a longitudinal slot therein, a blade normally confined within the

sheath and slideable through the outer end of the sheath, and means, including a hook and a shank, the latter connected to the blade through said slot, for sliding the blade out of and into the sheath, said hook lying normally beyond the inner end of the sheath and adapted to yieldingly ride upon and over the inner end of the sheath and slide upon the slotted face of the sheath, exerting frictional resistance to the outward movement of the blade, the said shank at its outer end lying normally within said slot against the blade and upon reaching the outer end of the slot during outward movement of the blade yieldingly riding over the outer end of the slot on to the face of the sheath to give frictional resistance to the outward movement of the blade and also to thereby offer frictional resistance to an inward movement of the blade, the free end of said shank being folded back upon itself to form a shoulder adapted to lie against the outer end of the sheath when the blade is fully projected.

7. An attachment for writing implements comprising a sheath and a sleeve, one side of the sheath having a longitudinal slot therein, a blade normally confined within the sheath and slideable through the outer end of the sheath, and means, including a hook and a shank, the latter connected to the blade through said slot, for sliding the blade out of and into the sheath, said hook lying normally beyond the inner end of the sheath and adapted to yieldingly ride upon and over the inner end of the sheath and slide upon the slotted face of the sheath, exerting frictional resistance to the outward movement of the blade, the said shank at its outer end lying normally within said slot against the blade and upon reaching the outer end of the slot during outward movement of the blade yieldingly riding over the outer end of the slot on to the face of the sheath to give frictional resistance to the outward movement of the blade and also to thereby offer frictional resistance to an inward movement of the blade, the free end of said shank being folded back upon itself to form a shoulder adapted to lie against the outer end of the sheath when the blade is fully projected, the connection between the hook and shank and the blade being located to engage the ends of the slot in the sheath, interchangeably, to limit the inward and outward movements of the blade.

In testimony whereof, I have hereunto set my hand.

SWAN PEARSON.
